UNITED STATES PATENT OFFICE.

JOHN W. CARTER, OF SOUTH ORANGE, NEW JERSEY.

DESIGN FOR A PAPER-BOX COVER.

Specification forming part of Design No. 5,134, dated July 25, 1871.

To all whom it may concern:

Be it known that I, JOHN W. CARTER, of South Orange, Essex county, New Jersey, have invented and produced a new and original Design for the Covers of Paper Boxes, of which the following is a specification:

The nature of my design is a calendar or register for the days of the month, with pointers to indicate the month and days of the month, as clearly shown in the photographic impression herewith.

I claim as my invention—

The design for the covers of paper boxes, as shown.

JOHN W. CARTER.
